UNITED STATES PATENT OFFICE.

ROBERT B. HIGGINS AND HERMAN ALBERS, OF ST. LOUIS, MISSOURI, ASSIGNEES TO
HIGGINS-ALBERS CONCRETE FORM COMPANY, OF ST. LOUIS, MISSOURI, A CORPO-
RATION OF MISSOURI.
CONCRETE-FLOOR DECKING.

1,034,913.

Specification of Letters Patent.

Patented Aug. 6, 1912.

Application filed May 24, 1911. Serial No. 629,218.

To all whom it may concern:

Be it known that we, ROBERT B. HIGGINS and HERMAN ALBERS, citizens of the United States, residing at St. Louis, State of Missouri, have invented certain new and useful Improvements in Concrete-Floor Decking, of which the following is a full, clear, and exact description, reference being had to the accompanying drawings, forming a part hereof.

Our invention has relation to improvements in concrete-floor deckings; and it consists in the novel details of construction more fully set forth in the specification and pointed out in the claims.

In the drawings, Figure 1 is a top plan of a portion of a concrete-floor decking with parts broken away, showing the application of our invention; Fig. 2 is a side elevation, part being shown dotted; Fig. 3 is a vertical cross-section on the line 3-3 of Fig. 1; Fig. 4 is a top plan of one of the sheet-holding clasps; and Fig. 5 is a side view thereof.

The present invention is an improvement on the floor decking forming the subject-matter of our pending application, Serial Number 556,235, filed April 18, 1910; and while contemplating the various objects and possessing the several advantages of the construction described in said pending application, the present improvement contemplates the introduction of specific details by which a saving of material may be effected; one which insures against the displacement of the sheets which directly support the concrete, once these sheets have been deposited on the support or false work on which they rest; and one possessing further and other advantages better apparent from a detailed description of the invention, which is as follows:

Referring to the drawings, 1, 1', representing respectively the main and supplemental floor-joists preferably of angle-bar construction, forming the upper part of the temporary or knock-down structure or "form" which supports the concrete while being poured. No attempt is made herein to illustrate the forms for casting the beams and posts, the invention being restricted to the floor decking. This decking comprises a series of thin metallic sheets *a*, *a*, laid over the joists (but not resting directly on them), the edge of one sheet overlapping the edge

of an adjacent sheet so as to form a lap-joint connection between the sheets and thus prevent any of the concrete leaking through between the sheets. In practice, these sheets are apt to shift and slip one over the other, so that the uniformity of the joints is disturbed. Moreover, in order that rigid economy may be practised in the use of the sheets, and that as few of the sheets as possible be employed to serve their purpose as a decking, it is desirable that the overlap between the sheets shall not only be reduced to a minimum, but that this overlap or lap-joint shall be maintained as uniform as possible. To this end we anchor the sheets to one another along the joint by a series of clasps or anchors, each clasp being composed of ribbon steel (or its equivalent) and bent so as to form a medial or body portion 2 having terminal resilient bends or loops 3, from which extend in either direction along the portion 2 and projecting beyond the loops, the spring arms 4, 4. The free ends of the arms 4 projecting beyond the body portion 2 (that is to say, beyond the loops 3) serve to guide the respective sheets *a*, *a*, in their insertion between the body 2 and the arms 4, 4, of the clasp, the edge of the sheet being forced to the bottom of the loop 3 (Fig. 4). In this way a uniform overlap between the sheets is insured, and the grip of the clasp or anchor arms on the sheets prevent any shifting of the latter during the progress of the work.

The sheets *a*, *a*, must necessarily be of thin material in order to avoid the formation of offsets or ridges in the surface of the concrete ceiling along the edges of the sheets, a thick plate being out of question as it would mar the face of the ceiling by producing a deep ridge. The thin ridges formed in the concrete by the sheets are almost imperceptible and may be readily planed down so as to be invisible.

A thin sheet of the character described of course, needs a suitable support to prevent sagging between the joists, and this support is in the nature of stiff, corrugated plates *b*, *b*, on the order of those employed in the construction of our pending application aforesaid, the stiffeners *b* being deposited on the joists 1, 1', and the sheets *a* being deposited on the sheets *b*.

C represents a concrete-floor poured on the deck-sheets *a*, and *B* (shown dotted in

Fig. 2) represents the beam merging with the floor, the parts shown in section in Fig. 3 being enlarged somewhat to better bring out the relation of the several elements of our invention. Parts shown but not referred to are well known in the art and require no description in the present connection. As shown in the drawings, the anchors or clasps are disposed across the lap-joint between the sheets *a*, and distributed to the required number along the joint. The sheets are thus effectively held against displacement, and economy in the use of the sheets results. In the dismantling of the false-work, the sheets are readily pulled away from the clasps, and the parts may be used again for the next job.

Having described our invention, what we claim is:

- 20 1. A concrete-floor decking comprising series of sheets of thin material with adjacent edges overlapped, clasps having each a medial or body portion interposed between the sheets and across the lap-joints formed by the sheets, and outer spring arms engaging the outer faces of the respective sheets and clasping the same to the medial portion, and corrugated sheets supporting the overlapped thin sheets, the bottom series of 25 arms of the clasps being adapted to rest in the depressions formed by the corrugations.
- 25 2. A concrete-floor decking comprising series of sheets of thin material with adjacent edges overlapped, clasps having each a medial or body portion interposed between the sheets and across the lap-joints formed by the sheets, and outer spring arms engaging the outer faces of the respective sheets and clasping the same to the medial portion, and corrugated sheets supporting the overlapped thin sheets, the bottom series of 30 arms of the clasps being adapted to rest in the depressions formed by the corrugations.

cent edges overlapped, clasps having each a medial or body portion interposed between the sheets and across the lap-joints formed by the sheets, and outer spring arms engaging the outer faces of the respective sheets, and clasping the same to the medial portion, and corrugated metal sheets supporting the overlapped thin sheets, the bottom series of 35 arms of the clasps engaging the corrugated sheets.

3. A concrete-floor decking comprising series of sheets of thin material with adjacent edges overlapped, clasps formed of a single strip of metal and having each a medial or body portion interposed between the sheets and disposed across the lap-joints between the sheets, and outer spring arms 40 extending in opposite directions from the opposite ends of the medial portion and terminating a suitable distance beyond the ends of the medial portion whereby the sheets are guided into position between the arms and medial portions, and corrugated sheets of metal for the support of the thin sheets 45 and the bottom series of arms of the clasps resting on the corrugated sheets.

In testimony whereof we affix our signatures, in presence of two witnesses.

ROBERT B. HIGGINS.
HERMAN ALBERS.
